HINGE SUPPORT PLATE

Alfred H. Bottom, 5801 Lawnview St. NW., and Richard C. Henson, 1323 12th St. NW., both of Canton, Ohio

Filed Jan. 20, 1966, Ser. No. 693

Term of patent 14 years

(Cl. D10—9)

FIG. 1 is a front elevation of a hinge support plate embodying our design.

FIG. 2 is a side view thereof.

FIG. 3 is a section taken along line 3—3 of FIG. 1 as viewed in the direction of the arrows.

FIG. 4 is a section taken along line 4—4 of FIG. 2 as viewed in the direction of the arrows.

FIG. 5 is a section taken along line 5—5 of FIG. 2 as viewed in the direction of the arrows.

The broken line disclosure on the drawing is for illustrative purposes only.

We claim:

The ornamental design for a hinge support plate, as shown and described.
